(57) **ABSTRACT**

A new cultivar of *Sedum* plant, 'Nonio' that is characterized by its foliage that emerges green in color and suffused with red-purple towards the apex and margins and matures to green centers with red-purple margins, its flowers in early summer that are purple-pink in color and emerge from flower buds that are pink in color, and its dense, very low-growing plant habit.

2 Drawing Sheets

1

Botanical classification: *Sedum spurium*.

Variety denomination: 'Nonio'.

CROSS REFERENCE TO A RELATED
APPLICATION

This application is co-pending with a U.S. Plant Patent Applications by the same Inventor and pertain to plants derived from the same parentage, the Applications are entitled *Sedum* Plant Named 'Nonov' (U.S. Plant patent application Ser. No. 12/660,465), *Sedum* Plant Named 'Nonob' (U.S. Plant patent application Ser. No. 12/660,436), *Sedum* Plant Named 'Nonol' (U.S. Plant patent application Ser. No. 12/660,411), *Sedum* Plant Named 'Noned' (U.S. Plant patent application Ser. No. 12/660,478), *Sedum* Plant Named 'Nonog' (U.S. Plant patent application Ser. No. 12/660,437), *Sedum* Plant Named 'Noner' (U.S. Plant patent application Ser. No. 12/660,492), *Sedum* Plant Named 'Nonet' (U.S. Plant patent application Ser. No. 12/660,479), *Sedum* Plant Named 'Nonia' (U.S. Plant patent application Ser. No. 12/660,438), *Sedum* Plant Named 'Nonef' (U.S. Plant patent application Ser. No. 12/660,502).

BACKGROUND OF THE INVENTION

The present invention relates to a new and distinct cultivar of *Sedum* plant, botanically known as *Sedum spurium* 'Nonio' and will be referred to hereinafter by its cultivar name, 'Nonio'. The new cultivar of *Sedum* is a hardy herba-

2

ceous perennial grown for use as a landscape and container plant and is particularly suitable as a groundcover.

'Nonio' was discovered in March of 2005 as a naturally occurring whole plant mutation at the Inventor's nursery in 5 Nunica, Mich. as a single unique plant in a containerized block of 100,000 seedlings of *Sedum spurium* 'Voo Doo' (not patented).

Asexual reproduction of the new cultivar was first accomplished by stem cuttings in Nunica, Mich. in June of 2007. 10 Propagation by cuttings and crown division has determined the characteristics to be stable and reproduced true to type in successive generations.

SUMMARY OF THE INVENTION

The following traits have been repeatedly observed and are determined to be the characteristics of the new cultivar. These attributes in combination distinguish 'Nonio' as a unique cultivar of *Sedum*.

- 15 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945
1. 'Nonio' exhibits foliage that emerges green in color and suffused with red-purple towards the apex and margins and matures to gray-green centers with red-purple margins.
  2. 'Nonio' exhibits flower buds that are pink in color.
  3. 'Nonio' exhibits flat-topped, rounded inflorescences with flower that are purple-pink in color and present in early summer.
  4. 'Nonio' exhibits a dense, very low growing habit with foliage that reaches about 3 inches in height.

The parent plant, 'Woo Doo', differs from 'Nonio' in having foliage that is maroon and green-tinged in color and in having pinkish purple flowers. 'Nonio' can be compared to other cultivars of *Sedum spurium* (all are un-patented) which differs from 'Nonio' in the following characteristics; 'Album Superbum' differs in having green leaves and white flowers, 'Bronze Carpet' differs in having variable green/maroon leaves and deep pink flowers, 'Coccineum' differs in having green leaves that are flushed with red under cool temperatures and crimson red flowers, 'Dragon's Blood' (syn. Schorbuster Blut) differs in having medium green leaves to green with red margins and red flowers, 'Elizabeth' differs in having variable green or maroon leaves and pink flowers, 'Fuldaglut' differs in having green and maroon leaves and rosy red flowers, 'John Creech' differs in having green leaves and pink flowers, 'Red Carpet' differs in having red leaves and pink flowers, 'Roseum' differs in having green leaves and pink flowers, 'Royal Pink' differs in having green leaves and pink flowers, 'Summer Glory' differs in having green leaves and pink flowers, and 'Tricolor' differs in having leaves that are green with white edges and pink flowers.

'Nonio' can also be compared to other cultivars that arose as a whole plant mutation of 'Voo Doo'; 'Nonol', 'Noner', 'Nonia' and 'Nonef'. 'Nonol' differs from 'Nonio' in having foliage that is green in color with red margins, in being slightly smaller in height, and in having flowers that are lighter pink in color. 'Noner' differs from 'Nonio' in having foliage with green centers and bright red margins and in having flowers that are less purple in color. 'Nonia' differs from 'Nonio' in having leaves that are less rounded in shape, leaf margins that are darker and maroon in color and in having flowers that are less purple in color. 'Nonef' differs from 'Nonia' in having foliage with greener centers when mature, having flowers that are less purple in color and in being slightly taller in height.

BRIEF DESCRIPTION OF THE DRAWINGS

40

The accompanying colored photographs illustrate the overall appearance and distinct characteristics of the new *Sedum*. The photographs were taken May (non-flowering) and July (flowering) of 2 year-old plants of 'Nonio' as grown in the ground in full sun in Nunica, Mich.

The photograph in FIG. 1 illustrates the foliage of 'Nonio'. The photograph in FIG. 2 provides a view of the flowers of 'Nonio'.

The photograph in FIG. 3 provides a top prospective and illustrates the plant habit of 'Nonio'.

The colors in the photographs may differ slightly from the color values cited in the detailed botanical description, which accurately describe the colors of the new *Sedum*.

DETAILED BOTANICAL DESCRIPTION

The following is a detailed description of the new cultivar as observed on 2 year-old plants of 'Nonio' as grown in the ground in full sun in Nunica, Mich. The phenotype of the new cultivar may vary with variations in environmental, climatic, and cultural conditions, as it has not been tested under all possible environmental conditions. The color determination is in accordance with The 2001 R.H.S. Colour Chart of The

60

65

Royal Horticultural Society, London, England, except where general color terms of ordinary dictionary significance are used.

General description:

Blooming period.—The last two to three weeks of June to the first or second week of July in Michigan.

Plant habit.—Herbaceous perennial, dense, low growing habit, mature plant sprawl from central crown with procumbent stems rooting as they contact the ground.

Height and spread.—Reaches about 3 inches in height (foliage) and about 6 inches in height in bloom, maximum spread in about 2 feet.

Hardiness.—Reliable hardy in U.S.D.A. Zones 4B to 7B.

Disease and pest.—No susceptibility or resistance to common diseases or pests has been observed.

Root description.—Fibrous and also readily produced at stem nodes.

Propagation.—Stem cutting spring through summer and crown division throughout the year.

Growth rate.—Moderate.

Stem description:

Stem shape.—Round.

Stem size.—3 to 4 inches in length and about $\frac{1}{8}$ inch in width.

Internode length.—Ranges from $\frac{1}{8}$ to $\frac{1}{4}$ inch.

Stem color.—185B.

Stem surface.—Glabrous.

Branching habit.—Well-branched.

Foliage description:

Leaf shape.—Rounded becoming elliptic to oblanceolate.

Leaf division.—Simple.

Leaf arrangement.—Opposite.

Leaf base.—Broadly cuneate.

Leaf apex.—Broadly acute to obtuse.

Leaf venation.—Not conspicuous, color matched leaf color.

Leaf margins.—Crenate to serrated with apex of young leaves papilose-ciliate.

Leaf attachment.—Petiolate.

Leaf presence and orientation.—Emerge upright becoming nearly horizontal.

Leaf surface.—Glabrous, waxy and semi-glossy on upper and lower surface.

Leaf color.—Young leaves, upper and lower surface; 139C and suffused towards margins with 187B, margins 187B, mature foliage upper and lower surface; 139C with thin margin of 187B.

Leaf size.—Young leaves; an average of $\frac{3}{4}$ inch length and $\frac{5}{16}$ to $\frac{7}{16}$ inch in width, mature leaves; an average of $\frac{3}{4}$ inch in length and $\frac{3}{4}$ inch width.

Petioles.— $\frac{1}{8}$ in length, $\frac{1}{16}$ in width, 139C in color, surface is glabrous.

Flower description:

Inflorescence type.—Dense, flat-headed cymes with 4 forked branches.

Inflorescence size.—An average of $2\frac{1}{2}$ inches in width and depth.

Lastingness of inflorescence.—About one month.

Flower type.—Perfect, spreading, 5-starred.

Flower number.—40 to 50 flowers per cyme.

Flower fragrance.—None.

Flower buds.—Conical in shape, about $\frac{3}{8}$ inch in length and $\frac{3}{16}$ inch in diameter, ribbed surface, 184C in color.

Flower size.—About $\frac{1}{8}$ inch in length and $\frac{3}{8}$ inch in diameter.

Peduncles.—Round, range from $1\frac{1}{2}$ inch to 2 inches in length, $\frac{1}{8}$ inch in width, 183D in color, glabrous surface.

Pedicels.—Round, range from $\frac{3}{8}$ inch to 1 inch in length, $\frac{1}{16}$ inch in width, 183D in color, glabrous surface.

Sepals.—5, spreading, ovate to lanceolate in shape, about $\frac{3}{8}$ inch in length and $\frac{1}{8}$ inch in width, 183B in color on both surfaces, entire margin, acute apex, truncate base, glabrous surface on both surfaces.

Petals.—5, spreading, lanceolate in shape, truncate base, acute apex, entire margin, color of inner and outer surfaces is 61A, glabrous surfaces on both surfaces.

5

10

15

Reproductive organs:

Pistils.—5, held erect, about $\frac{3}{8}$ inch in length, stigma $\frac{1}{32}$ inch in width and 61B in color, styles $\frac{1}{4}$ inch in length and 61B in color, ovary $\frac{1}{10}$ inch in diameter and 62D in color.

Stamens.—10, about $\frac{3}{8}$ inch in length, style 62B in color, anther 155A in color, pollen is sparse in quantity and N57A in color.

Fruit.—Rounded with pointed tip, aggregate, range from $\frac{1}{16}$ inch to $\frac{1}{8}$ inch in length and $\frac{1}{4}$ inch in width, 62A in color, seed production was not observed.

It is claimed:

1. A new and distinct variety of *Sedum* plant named 'Nonio' as described and illustrated herein.
